THUMB TACK

Victor A. Pompilio, Yonkers, N. Y.

Application October 20, 1938, Serial No. 235,925

2 Claims. (Cl. 40—25)

The present invention relates to an improvement in thumb tacks, and more particularly to a thumb tack which is to be used as an advertising medium.

5 The object of the invention is to provide a thumb tack which is inexpensive to manufacture, durable in structure, and can be assembled with great ease and celerity.

Another object of the invention is to provide 10 a thumb tack, having its head surface made of a suitable material whereby printed matter can be stamped thereon.

Another object is to provide a thumb tack 15 which is made up of two elements only, thereby reducing the cost of manufacture and assembly to a minimum. Other objects will be obvious as brought out in the following specifications:

Reference will be had to the accompanying drawing forming a part of this specification in 20 which similar reference characters indicate corresponding parts throughout the several views.

Figure 1 is a front elevation or face view of the present invention.

Figure 2 is a rear view of Figure 1.

25 Figure 3 is a section on the line 3—3 of Figure 1 looking in the direction of the arrows.

Figure 4 is a similar view to Figure 3, but showing the base plate partly in place.

Figure 5 is a side view of Figure 1, showing the 30 thumb tack fixed to a wall or the like, and

Figure 6 is a similar view to Figure 5 only showing a modified form of thumb tack.

Referring to the drawing, wherein I have shown by way of illustration merely, a thumb tack assembly, generally referred to by the numeral 10.

The thumb tack 10 consists of a disk shaped head or body portion 11 and a base plate 12 having a barb 13 punched out as shown at 14, Figure 2. The base plate 12 is made of resilient 40 material so that it may be capable of being bowed for insertion in bead 17. This base plate 12 is slightly bent at each end as shown at 15 and 16, for the purpose of which will be herein-after described. The disk shaped head or body portion 11 is bent down around its periphery to form an annular bead 17, the purpose of which will be hereinafter described. In assembling the thumb tack 10 the base plate 12, which is made of any suitable spring or resilient material, is 45 placed diametrically in the rear of the disk shaped head 11 and then sprung or arched into a position as shown in Figure 4, so that the ends 15 and 16 of the base plate 12 can easily pass under the rim 18 of the bead 17. The base plate 12

then is bowed and sprung into the position shown in Figures 2 and 3. It will be seen that this structure insures a firm grip on the disk shaped head, and allows the head to be easily rotated into proper reading position after the tack is inserted into a wall or the like.

Figure 6 illustrates a modified form of the present invention wherein the disk shaped head or body portion 11 is convexed on the outside. This structure tends to strengthen the head or body 10 portion when the tack is inserted into a wall or the like, and prevents denting the head with the thumb.

It will be seen from the description that the 15 tack is very desirable as an advertising medium. The tradesmen can give them away free to the consumer to tack in the wall adjacent to their telephone as a reminder, and to get the telephone number quickly.

The present invention can also be used as a 20 price marker. The tack can be inserted into the edge of a shelf holding merchandise, with the price of the merchandise printed on the head of the tack.

It will be seen that when the base plate 12 is 25 flat against the wall or the like it urges the ends 15 and 16 to bind upon the inside of the bead 17 thereby fixing the head or body portion 11 against accidental rotation after the printed matter is once fixed in its proper reading position. 30

It will be understood that many uses and modifications of this invention can be made without departing from the principles thereof.

Having thus described my invention, what I 35 claim as new and desire to secure by Letters Patent, is:

1. A device of the kind described comprising a disk shaped head or body portion having its peripheral edge bent back upon itself to form a bead, a rectangular resilient base plate slidably 40 mounted within said bead, and a barb integral with said base plate and bent at right angles thereto.

2. A device of the kind described comprising a disk shaped head or body portion having its peripheral edge bent back upon itself to form a bead, a resilient rectangular base plate having its ends diametrically mounted within said bead to permit the rotation of said base plate in respect to said head or body portion, and a barb 45 stamped out of said base plate and integral therewith.

VICTOR A. POMPILIO.
